DESIGN FOR A DOLL

Emeline Packard Miles, Peoria, Ill.

Application November 12, 1936, Serial No. 65,865

Term of patent 3½ years

To all whom it may concern:

Be it known that I, Emeline Packard Miles, a citizen of the United States, residing at Peoria, in the county of Peoria and State of Illinois, have invented a new, original, and ornamental Design for a Doll, of which the following is a specification, reference being had to the accompanying drawing, forming a part thereof.

Fig. 1 is a front view of a doll showing my new design;

Fig. 2 is a back view; and,

Fig. 3 is a side view of the same.

I claim:

The ornamental design for a doll as shown.

EMELINE PACKARD MILES.
